CLAIM

The ornamental design for a plumbing enclosure, as shown and described.

DESCRIPTION

FIG. 1 is a right, top, front perspective view of a plumbing enclosure embodying our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a cross-sectional view taken along line 8 —8 of FIG. 4;

FIG. 9 is a cross-sectional view taken along line 9 —9 of FIG. 2;

FIG. 10 is a cross-sectional view taken along line 10 —10 of FIG. 2;

FIG. 11 is a cross-sectional view taken along line 11—11 of FIG. 2; and,

FIG. 12 is a cross-sectional view of a second embodiment, the front elevational and top plan views being identical to those shown in FIGS. 2 and 4, and the other non-sectional views being mirror images of those shown in FIGS. 3 and 5 —7.

The broken line representations of holes in FIGS. 5, 11, and 12 are for the purpose of illustration only, and form no part of the claimed design.
